OPPOSED PISTON TYPE STEAM ENGINE

Peter Varis, New York, N. Y.

Application February 25, 1942, Serial No. 432,219

2 Claims. (Cl. 121—100)

This invention relates to improvements in steam engines, and more specifically to a steam engine having a plurality of opposed pistons reciprocably operating in a single cylinder.

One of the features of the invention resides in a steam engine in which the piston travel is relatively short to effect a faster speed of engine operation.

Another feature of the invention is to provide a steam engine capable of producing relatively great power in proportion to the size of the engine.

A still further feature of the invention is to provide a steam engine embodying a primary double head power piston directly connected to a crank shaft and a secondary opposed piston interposed between the heads of the double piston and cooperating therewith to define alternately functioning expansion steam chambers, power being simultaneously imparted to the primary and secondary pistons by the expansion of steam alternately admitted to the steam expansion chambers, there being mechanical means by which the power of the secondary piston is transferred to the primary double piston to effect an increase in power output of the engine.

Other features of the invention are to provide an opposed piston type steam engine which is simple of construction and operation; easy of piston repair and replacement; and smooth running and quiet of operation.

Other features of the invention will become apparent as the following specification is read in conjunction with the accompanying drawings, in which:

Figure 1 is a top plan view of a steam engine constructed in accordance with the invention.

Figure 2 is a vertical longitudinal sectional view on the line 2—2 of Figure 1, and illustrating the opposed pistons at substantially the limit of their stroke in one direction in full lines, and at the extreme limit of their stroke in an opposite direction in dotted lines.

Figure 3 is a horizontal sectional view on the line 3—3 of Figure 2.

Figure 4 is a vertical longitudinal sectional view of a modified form of the invention illustrating the opposed pistons at substantially the limit of their stroke in one direction in full lines, and at the extreme limit of their stroke in an opposite direction in dotted lines.

In the drawings I have illustrated my opposed piston type steam engine 10 as being vertically disposed and I shall describe it in terms consistent therewith, but it is to be understood that

the engine may be horizontally mounted if desired without departing from the spirit of the invention.

The steam engine designated in its entirety by the numeral 10, includes a vertical cylinder 11 which is open at its top and bottom. Suitably spaced steam ports 12 and 13 are provided in the wall of the cylinder, the opening and closing of which for the admission and exhaust of steam is controlled by the double slide valve 14 disposed within a steam chest 15. The steam chest 15 is of conventional construction and includes a steam inlet 16 and a steam exhaust 17. Further explanation of the construction and operation of the slide valve 14 will follow.

Reciprocable within the cylinder 11 is a double primary power piston A which includes a lower piston head 18, and an upper piston head 19, fixedly connected together in definite spaced

relation by two rods 20—20 disposed equidistantly from and diametrically disposed relative to the axis of the piston heads 18 and 19. The rods 20—20 pass through openings in the piston heads and to which they are fixedly connected.

The connection between the rods 20—20 and the piston head 18 comprises a flange 21 formed integral with each rod and abutting the inner side of the piston head, and a clamping nut 22 threaded to the rod and screwed tight against

the outer side of the piston head 18. The rods 20—20 are connected to the piston head 19 by pairs of clamping nuts 22'—22' threaded to the rods and tightly abutting the inner and outer sides of the said head.

The lower piston head 18 is connected by a wrist-pin connection 23 to the top end of a connecting rod 24. The lower end of the connecting rod 24 is connected by a bearing 25 to the crank 26 of a crank shaft 27, the latter being rotatably journaled in fixed bearings 28. From the description thus far, it will be understood that the piston heads 18 and 19 move simultaneously in the same direction as the power piston A reciprocates and they provide closure means

for the open ends of the cylinder 11. The piston heads 18 and 19 are provided with conventional piston rings 29 in sealed wiping engagement with the inner wall of the cylinder 11. Reciprocably disposed within the cylinder 11 intermediate the piston heads 18 and 19 of the double power piston A is an opposed piston B comprising a piston head 30 having spaced openings 31—31 therein through which the rods 20—20 freely pass. Leakage of steam through the openings 31—31 is prevented by packing glands 32

which are carried by the piston head 30 and which surround the rods 20-20. Fixedly connected to the piston head 30 axially thereof and rising vertically therefrom is the lower end of a piston rod 33. The rod 33 freely passes through a central opening 34 in the upper piston head 19, and the upper end of said rod extends beyond the piston head 19 for a reason to be hereinafter appreciated. Leakage of steam through the opening 34 is prevented by a packing gland 35 carried by the outer side of the piston head 19 and which surrounds the rod 33.

The upper end of the piston rod 33 is mechanically connected to the double power piston A for the purpose of transferring power from the piston B to the power piston unit A during operation of the engine. The connecting mechanism includes diametrically opposed rock-levers 36-36 pivotally mounted in bearings 37-37 disposed at the top of the cylinder 11. The rock-levers extend radially with respect to the axis of the cylinder and have their inner ends respectively flexibly connected to the top ends of the rods 20-20 by means of short pivotal links 38-38. The outer ends of the rock-levers are pivotally connected to rods 39-39. Each rod 39 is sectional and embodies a turnbuckle 40 for facilitating adjustment of the length of the same. The other ends of the rods 39-39 are respectively pivotally connected to the ends of a head 41 which is fixedly attached to or integral with the top end of the connecting rod 33. Thus it will be understood that as the intermediate piston head 30 moves up and down relative to the fixedly spaced piston heads 18 and 19, power from the piston head 30 will be transferred to the double power piston A and impart additional power thereto.

The space between the piston head 18 and opposed piston head 30 constitutes a lower steam expansion chamber C which is reduced in size as the piston heads 18 and 30 move toward each other, and becomes enlarged as they move away from each other by the expansion of steam admitted to the chamber. The port 12 constitutes the steam inlet and outlet for the lower steam chamber C.

The space between the upper piston head 19 and the piston head 30 constitutes an upper steam expansion chamber D which is reduced in size as the piston heads 19 and 30 move toward each other, and become enlarged as they move away from each other by the expansion of steam in the steam chamber D. The port 13 constitutes the steam inlet and exhaust for the steam chamber D.

Referring back to the slide valve 14, the same is provided with suitably spaced steam inlet passages 42 and 43 for timed alternate registration with the ports 12 and 13 respectively as the opposed intermediate piston head reaches the limit of its movement in opposite directions. The inlet passages 42 and 43 open into the steam chest 15. The slide valve is also provided with suitably spaced exhaust passages 45 and 46 which alternately register with the ports 12 and 13 respectively in timed relation to exhaust steam from the chambers C and D at the limit of the expansion strokes of the pistons. The exhaust passages 45 and 46 register with a manifold or exhaust outlet leading to the common exhaust 17 when the same are respectively registering with the ports 12 and 13.

The movement of the valve 14 is timed and mechanically controlled by a cam 47 fixed to the

crank shaft 27. A rod 48 is fixed to the lower end of the slide valve 14 and is slidably mounted in a bearing 49 extending from one of the bearings 28. The lower end of the rod 48 freely rides against the periphery of the cam 47.

In Figure 1 of the drawings, the piston heads 18 and 30 are nearing the limit of their movement toward each other, the crank being approximately on center. The piston 19 is at the top of the cylinder at approximately the limit of its upward movement. As the crank 26 moves past center, the inlet passage 43 of the steam slide valve registers with the port 12 and simultaneously the exhaust passage 46 registers with the port 13. Thus steam from the steam chest 15 enters the steam chamber C defined by the closely positioned piston heads 18 and 30, and simultaneously the expanded steam from the steam chamber D is exhausted through the port 13, passage 46 to the steam exhaust pipe 17. The valve 14 moves to close the ports 12 and 13 whereupon the expansion of the steam in the chamber C forcibly moves the pistons 18 and 30 away from each other. Power from the piston A is therefore directly transmitted from the piston head 18, connecting rod 24, and crank 26 to the crank shaft 27. Power from the upstroke of the piston head 30 is indirectly transferred from the piston B to crank shaft 27 through the piston A by the mechanical connecting means consisting of the connecting rod 33, rods 39, rock levers 36 and flexible coupling links 38 to the rods 20. Similarly, the power is transmitted from pistons A and B during the power upstroke of the piston A and downstroke of the piston B. Power for the stroke just mentioned is obtained by the admission of steam through the port 13 by registration of the inlet passage 43 therewith, at which time the piston heads 30 and 19 are in relatively close relation, reducing the size of the chamber D, and the piston head 18 is at the lower end of the cylinder 11 as illustrated in dotted lines. Also, at this time the exhaust passage 45 is in register with the port 12 to exhaust steam from the chamber C. Thus by the timing movements of the steam slide valve 14 by the actuation of the cam 47, the pistons 18, 19 and 30 will reciprocate in the manner hereinbefore described, that is, power from the double piston A and opposed piston B is transmitted to the crank shaft twice on each revolution thereof.

From the foregoing description it will be understood that the steam engine 10 is relatively simple and compact in construction; that the pistons are accessible for easy removal for replacement of parts and repair; and that the strokes of the pistons are relatively short which is indicative of faster speed and smooth operation.

In practice, the exhaust from the exhaust pipe 17 before passing to a condenser or to the atmosphere, may be connected by means of a valve, to a series of three cylinders, the first cylinder being known as "H. P." (high pressure), the second "I. P." (intermediate pressure), and the third, "L. P." (low pressure). However, if a single cylinder steam engine is constructed in accordance with this invention, the exhaust is direct to a steam condenser or to the atmosphere.

In Figure 4 there is shown a modified form of the invention in which the fixed coupling means between the piston heads of the double power piston is disposed exteriorly of the cylinder instead of within the cylinder as shown in Figure 2. In this form, the cylinder 11, steam chest 15, and crank shaft 27 are the same as in the form shown

in Figure 2, and like reference characters refer to like parts. In this modified form, the fixedly spaced piston heads of the power piston A' are designated 18a and 19a, the piston head 18a being directly connected to the crank shaft 27 by the connecting rod 24. Connected to the piston head 18a and extending upwardly therefrom is a rod 33a. The rod 33a is secured to the head 18a axially thereof and is connected thereto by nuts 50-50 which are threaded to the threaded portion 51, the said nuts tightly abutting the respective opposed sides of the head. The rod 33a extends upwardly through an oversize axial opening 53 in the head 19a, the upper end of the said rod being screw threaded as at 54 to which a cross arm 41a is connected. The threaded end 54 passes through the cross arm and has clamping nuts 55-55 threaded thereto and tightly fitting against the respective opposed sides of the cross arm. Spacer rods 20a-20a connect the cross arm 41a and piston head 19a, said rods being disposed equi-distantly from and diametrically disposed relative to the axis of the center rod 33a. The ends of the rods 20a-20a are threaded to receive nuts 56 which tightly secure the rods to the cross arm 41a and piston head 19a.

Slidably telescoping the rod 33a is a tubular rod 57, the inner end of which is externally screw threaded for threading engagement with a central threaded aperture 58 provided in the intermediate opposed piston head 30a. Clamping nuts 59 are threaded to the tubular rod 57 and tightly engage the walls of opposed countersinks in the opposed sides of the piston head 30a. The upper end of the rod 57 freely passes through the openings 53 to extend beyond the piston head 19a, and this extending end of the rod 57 is provided with a head 60. The joint between the head 60 and the rod 33a is sealed by a packing gland 61. A similar packing gland 62 seals the joint between the tubular rod 57 and the walls of the opening 53 to prevent leakage of steam from the steam chamber D', said chamber being formed by the opposed piston heads 19a and 33a. The second steam chamber C' is formed between the piston head 30a and the piston head 18a. From the description thus far of the modified form of engine it will be understood that the piston heads 18a, 19a, and the cross arm 41a may reciprocate as a single unit, and that the single intermediate piston head 30a is reciprocable relative thereto. However, power from the piston 30a is transferred to the double or power piston A' by mechanical means disposed exteriorly of the cylinder 11. This mechanical means includes rock-levers 36a-36a pivotally mounted in bearings 37-37 disposed in diametrically opposed relation at the top of the cylinder 11. The rock levers extend radially with respect to the axis of the cylinder and have their inner ends pivotally connected to the upper ends of links 38a-38a, said links having their lower ends pivoted to ears 63 extending from the head 60. The inner ends of the levers 36a are bifurcated or forked to permit them to clear the rods 20a. Pivoted to the outer forked ends of the rock levers 36a-36a are the lower ends of links 39a-39a, the upper ends of said links being pivotally connected to the cross arm 41a.

The operation of the modified form of the

invention as set forth in Figure 4 is the same as that previously described, except the mechanical means by which the power from the intermediate piston head is transmitted to the double head piston A'. As the piston head 30a reciprocates under the alternate expansion of steam in the steam chambers C' and D', power therefrom is transmitted to the cross arm 41a by the actuation of the links 38a-38a, rock levers 36a-36a, and links 39a-39a to the cross arm 41a, and thence from the cross arm directly to the piston head 19a by the connecting rods 20a-20a and to the piston head 18a by the piston rod 33a.

By the novel construction and arrangement of parts as set forth in the modification shown in Figure 4, the pistons and their connecting parts are readily accessible for disconnection and reassembly when repair or replacement of such parts becomes necessary. The thread and nut connections between the cross arm 41a and the rods 20a-20a, and 33a facilitates adjustment of the strokes of the piston heads when wear between the levers and links occur.

While I have shown and described what I consider to be the preferred embodiments of my invention, I wish it to be understood that such changes in design and construction as come within the scope of the appended claims may be resorted to if desired without departing from the spirit of the invention.

Having thus described the invention, what I claim as new and desire to secure by Letters Patent of the United States:

1. In a steam engine, a cylinder open at both ends, a primary piston slidable in said cylinder comprising an upper and lower piston heads, a connecting rod fixed to the lower piston head and freely passing through the upper piston head and extending therebeyond, a cross arm fixed to the extending end of said rod, an intermediate piston head disposed within said cylinder between said upper and lower piston heads, rods connecting the cross arm to the upper piston head, a tubular rod slidably telescoping the connecting rod and having its inner end fixedly connected to said intermediate piston head and its other end freely passing through and beyond the upper piston head, the spaces between opposite sides of the intermediate piston head and the upper and lower piston heads constituting separate steam chambers, a pair of spaced ports in the cylinder opening into the respective steam expansion chambers, means for alternately admitting steam to the expansion chambers and for exhausting the same therefrom, means connecting the free extending end of the tubular rod to the cross arm for transmitting power from the intermediate piston to the primary piston, a crank shaft, and a connecting rod connecting the lower piston head of the primary piston to said crank shaft.

2. In an engine as set forth in claim 1, in which the means connecting the tubular rod to the cross arm comprises opposed rock-levers pivoted at the top of the cylinder, links connecting one of the ends of the rock-levers to the cross arm, and links connecting the other ends of the rock-levers to the extending end of the tubular rod.

PETER VARIS.
